UNITED STATES PATENT OFFICE.

ISAAC HIRSOHN, OF NEW YORK, N. Y.

GARBAGE-CAN.

No. 821,241.

Specification of Letters Patent.

Patented May 22, 1906.

Application filed May 4, 1905. Serial No. 258,873.

To all whom it may concern:

Be it known that I, ISAAC HIRSOHN, a citizen of the United States, residing in New York, in the borough of Manhattan and 5 State of New York, have invented certain new and useful Improvements in Garbage-Cans, of which the following is a specification.

This invention relates generally to cans 10 such as used for containing garbage, ashes, rubbish, and the like, but more particularly to garbage-cans, and has among its objects the provision of a receptacle of this type having means in connection therewith for enabling the cover to be securely locked thereon in order to prevent the disturbance of the contents by unauthorized persons.

The invention also purposed the provision of a can in which the cover-locking devices 20 are so arranged as to materially reinforce the cover and body.

The invention further aims to provide a can of the class mentioned in which the cover although intended to be locked on the body 25 at only one point by a padlock or similar device is readily detachable from the body upon the unlocking of said padlock or other device in order that the can may be conveniently handled while dumping the same.

30 The novel features of the invention will hereinafter appear and be defined in the appended claim.

In the accompanying drawings, in which similar characters of reference denote identical parts throughout the several views, 35 Figure 1 is a side elevation of a can constructed in accordance with the invention, showing the same in closed and locked position. Fig. 2 is a vertical central section 40 thereof, the locking device being omitted; and Fig. 3 is a top plan view of the can shown in Fig. 1.

The body 1 of the improved garbage-can is formed of sheet metal in the usual manner, 45 being provided at the sides with upright guard-strips 2, which are so twisted as to have their side edges project outwardly from the periphery of the can-body in order to protect the same against injury, said strips 50 being riveted to the hoops at the upper and lower edges of the can-body, as shown. The lower exterior hoop 3 extends downwardly below the bottom of the body 1 and constitutes a base or rest for the same. A rein-

forcing-strip 4 extends downwardly from a 55 point adjacent the upper edge of the can-body, upon which it is disposed longitudinally diametrically across the bottom thereof and up the opposite side, as shown in Fig. 2, being retained beneath the hoop 3 and firmly 60 attached to the sides of the can-body by means of rivets or in any suitable manner, although spaced from the bottom thereof. One end of the strip 4 is bent outwardly at approximately right angles to the body and 65 provided with an aperture, thus constituting a perforated ear 5, while the opposite end of said strip is bent outwardly in substantially the same manner, but in addition is bent into a terminal transverse bead 6. The strip 70 4 is also provided with an aperture or opening 7, preferably of rectangular shape, which is adjacent the bead 6; as shown in Fig. 2.

Reference-numeral 8 indicates the cover of the improved garbage-can. Said cover is 75 adapted to fit over the body 1, as shown, and is provided at its lower edge with an exterior hoop 9, similar to the hoop 3 at the bottom edge of the can-body, the hoop 9 serving to position a cross-strip 10, which extends diametrically of the upper face of the cover and passes at both ends beneath and beyond said cross-strip. The ends of said cross-strip are thus disposed diametrically of the cover and are bent outwardly from the side wall of the 80 same, one end being bent into the form of an upwardly-directed hook 11, adapted to pass through the aperture 7 in the ear constituted by one end of the body-embracing strip 4, said hook engaging the terminal bead 6, as 85 shown in Fig. 2, and being pivotally supported thereon. The opposite end of the cross-strip 10 is formed into an outwardly-projecting perforated ear 12, similar to and adapted to register with the ear 5, constituted by the perforated end of the strip 4. The cross-strip 10 is provided intermediately 90 with openings through which pass the laterally-bent ends of a handle 14, said ends being firmly seated and retained on the cover below said cross-strip, as shown in Fig. 2.

As has been stated, the hook 11 embraces the bead 6 in such a manner as to form a hinged support for the cover 8; but said cover is readily detachable when tilted so far as to 100 release said hook. In order to lock the cover upon the body of the can, a padlock 15 or similar device is passed through the perfor-

- rated ears 5 and 12 and locked, said padlock thus preventing the unhinging of the cover at the opposite side thereof. It is evident, however, that upon unlocking the padlock 5 the cover may be detached from the body after the same has been sufficiently tilted so that the can may be readily dumped. The padlock is preferably attached to the side wall of the can-body by a chain 16.
- 10 By the improved locking means described the improved garbage-can may be closed in such a way as to make it practically impossible to open it without necessitating the total destruction thereof, inasmuch as the 15 cross-strip of the cover and the body-embracing strip effectively prevent the displacement of the several parts. It is therefore possible to prevent any disturbance of the contents of the can by meddlesome persons.
- 20 In practice the garbage-collectors are furnished with a master-key which serves to unlock the various cans upon their routes, so that practically no loss of time is caused. It is obvious, however, that although I have 25 described the improved can as being particularly designed for containing garbage it may also be used to contain ashes, rubbish, and the like.

Having thus described my invention, I claim as new and desire to secure by Letters 30 Patent—

A garbage-can comprising a body, a longitudinally-disposed reinforcing-strip attached to the sides of said body and extending across the bottom thereof, the ends of 35 said strip being disposed adjacent the upper edge of the body and extending outwardly at approximately right angles therefrom, one of said ends being provided with a bead and the other having an aperture therein, a cover fitting over said body, and a cross-strip upon the upper face of said cover extending outwardly at its ends at approximately right angles to the sides of the cover, one end of 40 said cross-strip being pierced with an aperture registering with the aperture in said reinforcing-strip, and the other end being provided with a hook embracing said bead.

In testimony that I claim the foregoing as my invention I have signed my name in 45 presence of two subscribing witnesses.

ISAAC HIRSOHN.
